UNITED STATES PATENT OFFICE

ARVIE B. HENSLEY, OF BLUEFIELD, WEST VIRGINIA

WICK LIFTER

REISSUED

Application filed May 21, 1929. Serial No. 364,820.

This invention relates to new and useful improvements in liquid fuel burners and more particularly to a burner of the wick type. The principal object of this invention is to provide means whereby a wick may be lifted in a burner without touching the wick with the hands.

Another important object of the invention is to provide a wick lifter for burners which can be quickly operated without inconvenience to the person actuating the same.

These and other important objects of the invention will become more apparent to the reader after considering the invention as described and claimed hereinafter.

In the drawings:

Figure 1 represents a side elevation of the improved wick lifter mounted on a burner.

Figure 2 represents a fragmentary side elevation showing the wick lifter mounted on a burner.

Figure 3 represents a vertical sectional view taken substantially on the line 3—3 of Figure 2.

Figure 4 represents a horizontal sectional view taken substantially on the line 4—4 of Figure 3.

Figure 5 represents a horizontal sectional view taken substantially on the line 5—5 of Figure 3.

Figure 6 represents a horizontal sectional view, taken substantially on the line 6—6 of Figure 1.

Figure 7 represents a horizontal sectional view, taken substantially on the line 7—7 of Figure 1.

Referring to the drawings, wherein like numerals designate like parts, it will be seen that the present invention is adapted for use on a burner such as employ wick feed tube 5. In the present instance, this feed tube is shown threaded at its lower portion 6 for threaded engagement through the upper end of a fuel container 7.

The invention consists of a sleeve 8 for snug slidable engagement on the tube 5 and this sleeve is provided with a circumferentially extending channel 9, adjacent its lower end. A pin 5' and a slot 8' co-act to provide

8, to permit the sleeve to slide on the tube, but to prevent the rotation thereof on the said tube. The upper end of the sleeve is provided with an enlarged hollow cylinder 10, the periphery of which is grooved to receive a two-part annulus generally referred to by numeral 11. The annulus 11 is composed of sections 12—12 which have ears 13 at their ends between which are pivotally connected, by means of pins 14, depending arms 15. The intermediate portion of each arm is offset inwardly as at 16, so that the lower portion of the arm will be disposed in close spaced parallelism with respect to the sleeve 8.

The lower end of each arm 15 is provided with a lateral lug 17, for pivotal connection between the ears 18 at the ends of the sectional ring 19 rotatable in the aforementioned channel 9.

A spring 20 is convoluted in the groove 9 and about the sleeve 8 and has one end anchored in the said sleeve, while its opposite end is anchored to the ring 19 as shown in Figure 5.

The annulus 11 and periphery of the cylinder 10 are provided with a pair of registering openings 21 and 22 respectively at diametrically opposite points. Within each opening 21 of the annulus 11 is mounted a vertical roller 23, while protruding through the registering openings are cam members 24 extending from their pivot points 25. Each of these cam members is provided with a jaw 26 for engagement against opposite side portions of the wick denoted by numeral 27.

As is clearly shown in Figure 2, the wick tube 5 is provided with pintles 28 projecting from diametrically opposite side points and are adapted to be normally engaged by hook members 29 depending from the ring 19.

It will thus be seen that in order to operate the wick, the cylinder 10 is grasped in the hand and rotated so as to disengage the hook member 29 from the pintles 28—28. The rotation of the cylinder 10 in the act of disengaging the said hook members causes the rollers 23 to ride against the cam surface of the cam 24, which results in the inward movement of the jaw members 26 against the wick 27 to firmly retain the same.

When the hook members have been disengaged, the sleeve 8 is then lifted and obviously the clamped position of the wick 27 between the jaws 26 results in the lifting of the wick. By releasing the cylinder 10, the spring 20 will unwind, rotating the sleeve 8 and causing the disengagement of the jaws 26 and in the downward movement of the sleeve, the same will result in the free engagement of the hook members 29 with the pintles 28-28.

While the foregoing description has been in detail, it is to be understood that numerous changes in the specific shape, size and materials may be resorted to, without departing from the spirit and scope of the invention as claimed hereinafter.

I claim:

1. A wick lifter for burners including a wick tube, a sleeve slidable on the tube, a hollow head on the sleeve, cam members within the hollow head for clamped engagement with the wick, and means for engaging said cam members with the wick so that by sliding the sleeve upwardly the wick will be lifted, said means consisting of an annulus rotatably mounted about the hollow head, cam means on the cam members, and rollers on the annulus for engagement with the cam to cause the cam members to clamp against the wick when the annulus is rotated about the hollow head.
2. A wick lifter for burners including a wick tube, a sleeve slidable on the tube, a hollow head on the sleeve, cam members within the hollow head for clamped engagement with the wick, and means for engaging said cam members with the wick so that by sliding the sleeve upwardly the wick will be lifted, said means consisting of an annulus rotatably mounted about the hollow head, cam means on the cam members, and rollers on the annulus for engagement with the cam to cause the cam members to clamp against the wick when the annulus is rotated about the hollow head, and means for retaining the cam members in wick disengaged position.

In testimony whereof I affix my signature.

ARVIE B. HENSLEY.
